C. M. SMART

BANK PROTECTING DEVICE

Filed March 17, 1927

UNITED STATES PATENT OFFICE.

CARROLL M. SMART, OF DETROIT, MICHIGAN.

BANK-PROTECTING DEVICE.

Application filed March 17, 1927. Serial No. 176,183.

This invention relates to bank protecting devices, and the object of the invention is to provide a means for passing articles through a bank teller's window without exposing the teller to robbery by persons on the outside of the window.

A further object of the invention is to provide a teller's window of the character described backed up with bullet-proof glass and arranged so that a gun cannot be inserted through any part of the window opening.

A further object of the invention is to provide a rotatable table or deal tray by which articles may be passed from the exterior to the interior of the teller's window, the teller's window extending in close proximity to the upper edge of the deal tray.

Another object of the invention is to provide a deal tray having partitions dividing the tray into compartments, the partitions preventing the use of a gun between the lower edge of the bullet-proof window and the bottom of the tray.

These objects and the several novel features of the invention are hereinafter more fully described and claimed, and the preferred form of construction by which these objects are attained is shown in the accompanying drawings in which—

Fig. 1 is an elevation of a teller's window equipped with my bank protecting device.

Fig. 2 is a section taken on line 2—2 of Fig. 1.

Fig. 3 is a section taken on line 3—3 of Fig. 2.

Fig. 4 is a section through an alternative form of construction.

As shown in Fig. 2 a housing 1 is provided which is formed from cast bronze and is secured on the usual shelf provided at the teller's window. This bronze housing, as shown in Fig. 3, is of sufficient depth to receive the rotatable table or deal tray 2. The deal tray 2 is also formed of cast bronze and the bronze in both the housing and tray is sufficiently soft so that a bullet will tend to embed therein rather than glance off. The deal tray is set into an opening in the housing 1 so that the upper edge of the deal tray is flush with the upper surface of the housing. A channel 3 extends across the up-

per surface of the housing and is adapted to receive a bullet-proof glass panel 4. A stem 5 is secured to the center of the channel 3 and extends downwardly through a boss provided therefor in the deal tray 2 and is supported at the bottom in a member 6 shown in Fig. 3.

A ball thrust bearing 7 is positioned between the deal tray and the member 6 so that the deal tray is freely rotatable about the stem 5. The channel 3 is secured at the opposite ends to the upper surface of the housing 1. In the form shown in Figs. 1, 2 and 3 a bronze wicket 8 is provided in front of the teller's window and the bullet-proof glass 4 is mounted behind the wicket 8 in the bronze channel 3 which encloses the bullet-proof glass panel. This glass panel, as shown in Fig. 2, is spaced from the posts 9 by the spacing members 10 so that when the customer speaks to the teller the teller may readily hear what is said.

The deal tray is divided into pockets by means of partitions as shown in Fig. 2 and these partitions extend to the same plane as the outer flange of the tray and are so arranged as to just clear the channel 2 and prevent the possibility of a gun being inserted between the bottom of the flange 2 and the bottom of the deal tray and used with any telling effect. The main pockets 11 provided in the deal tray are for the receipt of depositor's money and bank book or checks and other papers normally used in banking.

The surface 12 of the housing shown in Fig. 2 provides a place for the articles picked out of the deal tray by the teller. This device may also be used for ticket windows and other places of like character where a safe means for transacting business of this character is desired.

An alternative form of the invention is shown in Fig. 4 in which the shelf for the teller's window is recessed at 13 to provide a space for the deal tray. In this form the housing 1 is not required while the deal tray and other parts are the same as shown in Figs. 2 and 3. In this form the channel 3 extends across the top of the deal tray and supports the bullet-proof glass 4 which is apertured to receive a speaking tube 5. This speaking tube 5 is preferably provided with

shutters which allow sound to travel therethrough but prevent the possibility of shots passing therethrough. In this form the bullet-proof glass 4 may be a part of the front 5 of the teller's cage. In either case the device is operated by placing the bank book in one of the pockets 11 and turning the deal tray to bring the bank book to the teller or to the customer as desired.

10 It is to be understood that the wicket indicated at 8 does not form a part of this invention, it being merely shown as one of the structures with which this invention may be incorporated, and that the wicket 15 may be entirely removed from between the frame members or pilasters 9 so that the front of the teller's window is simply a glass partition which may occupy the position back of the pilasters as shown in Fig. 2 or 20 otherwise as may be desirable. In any event the rotatable tray at the teller's window should have its axis approximately in the plane of the bullet-proof glass.

Having thus fully described my invention 25 what I claim and desire to secure by Letters Patent of the United States is—

1. In a bank protecting device, the combination with a compartment the front wall of which is formed of two parts, the upper 30 part being of bullet-proof glass supported upon the lower part, a portion of the upper part being arranged to form a glassed teller's window, a rotatable deal tray at the teller's window having a series of partitions 35 and a peripheral flange providing pockets open at the top in a horizontal plane, there being a recess in which the tray is rotatably mounted with the upper faces of the partitions and flange practically flush with the 40 lower edge of the glass of the teller's window which extends diametrically thereacross, the parts being associated as to permit unrestricted revolution of the tray on its axis and the partitions being so arranged 45 as to prevent introduction of a gun barrel beneath the lower edge of the glass of the teller's window in any position of the tray.

2. In a bank protecting device, the combination with a compartment, the front wall 50 of which is formed of an upper bullet-proof glass portion and a lower part provided with a ledge on which the lower edge of the glass portion is supported, a portion of the said upper part having spaced frames defining a teller's window, there being bullet-proof glass extending between the frames, a metal member supported by the lower portion of the said wall and extending beneath the lower edge of the glass of the teller's 60 window, said member having a circular opening, a circular deal tray rotatably supported in the opening of the metal member and having a series of vertical partitions and a peripheral flange, the upper edge of 65 which is substantially flush with the top

surface of the metal member, a channel member extending across the opening of said metal member supporting the lower edge of the glass of the teller's window, the upper edge of the said partitions riding in 70 close relation with the said channel and defining pockets open at the top in a horizontal plane permitting articles to be moved from one side of the teller's window to the other beneath the said channel. 75

3. In a bank protecting device, the combination with a partition having a teller's window therein, said window having a bullet-proof glass portion, a metal member positioned beneath the lower edge of the glass, 80 a channel member extending across the metal member in which the glass edge rests, said member having a circular aperture, a circular tray rotatably mounted in the said aperture, a central shaft at the axis of the 85 tray, anti-friction bearings for the said tray permitting the same to be freely rotated, the said shaft having a part at its upper end set into the metal of the channel, the said tray having a series of partitions and a peripheral flange defining pockets, the upper 90 surface of the partitions and the flange being practically in the same plane as the lower face of the channel tending to close the interstice or space between the channel 95 and the bottom of the tray above its axis and thereby preventing introduction of a gun barrel below the channel member, the said upper surface of the partitions further being substantially flush with the upper surface of the member on which the channel 100 rests.

4. In a bank protecting device, a deal tray for a glassed teller's window comprising a metal base member having an aperture and 105 a tray rotatably supported in the said aperture, the said tray having a series of partitions extending in different directions and a peripheral flange providing open pockets or recesses, the upper edge of the partitions 110 and flange being substantially flush with the upper surface of the metal member, a U-shaped channel member extending across the said aperture over the tray for receiving 115 the lower edge of the glass of the teller's window.

5. In a bank protecting device, the combination with a partition including spaced frames defining a teller's window, of a metal grille extending between the frames in the 120 plane of the partition, a bullet-proof glass positioned to the rear of the grille and extending across the opening between the frames and spaced therefrom at the rear providing narrow openings between the respective edges of the glass and frame, a metal member positioned between and at the base of the said frame members having a circular recess and an upper substantially 125 plane surface, a circular deal tray mounted 130

to rotate in the said aperture on a vertical axis in the plane of the said glass member, a supporting member for the lower edge of the glass extending diametrically across the opening in the said member, the said rotatable tray having vertical walls defining pockets open at the top in a horizontal plane

for deposition of articles, the upper edges of said walls being in substantially the same plane as the said plane surface of the metal member. 10

In testimony whereof I sign this specification.

CARROLL M. SMART.
